UNITED STATES PATENT OFFICE.

ARTHUR E. SHAW AND EDWARD S. SANDERSON, OF PHILADELPHIA, PENNSYLVANIA, ASSIGNORS TO THE PENNSYLVANIA GLOBE GAS LIGHT COMPANY, OF PHILADELPHIA, PENNSYLVANIA, A CORPORATION OF PENNSYLVANIA.

STREET-LIGHT.

SPECIFICATION forming part of Letters Patent No. 687,663, dated November 26, 1901.

Application filed August 2, 1901. Serial No. 70,656. (No model.)

To all whom it may concern:

Be it known that we, ARTHUR E. SHAW and EDWARD S. SANDERSON, citizens of the United States, residing at Philadelphia, in the county of Philadelphia and State of Pennsylvania, have jointly invented certain new and useful Improvements in Street-Lights, of which the following is a specification.

The invention relates to street-lights, and 10 more particularly to sign-holders for the same, the object being to provide simple, efficient, comparatively inexpensive, and readily adjustable and detachable means for supporting advertising-signs of the sort usually associated with street-lights.

To the ends stated the invention consists in the improvements hereinafter described and claimed.

The nature, characteristic features, and 20 scope of the invention will be more clearly understood by reference to the accompanying drawings, forming a part hereof, in which—

Figure 1 is an elevational view of a Welsbach street-light with our improved sign-holder applied. Fig. 2 is a sectional view of the sign-holder, and Fig. 3 is a perspective view of separate parts of the holder.

Having reference to the drawings, 1 indicates the base or that part of the holder which 30 is normally stationary, and the same has its top flanged and provided with an open slot 2 to afford ready means of attachment to a suitable part—for instance, the ring *a*, which supports the dome of the lamp. The lower 35 edge of the base is transversely extended, as at 3, and provided with a flange or heel 4, upon which rests the glass sign-section *b*. There is also provided on said stationary member a longitudinally-ranging raised part 40 or seat 5, which is in a common plane with the edge of the flange 4, and said raised portion or seat is served with countersunk parts 6 for the reception of screws or bolts 7. The seat 5 may be cast with the base member or 45 be otherwise applied thereto.

8 is a thin metal plate of the general shape of the base, being provided with transverse portions 9, which coöperate with the arms 3 of the base to hold the sign-section in posi-

tion. The keeper or member 8 has the transversely-extending slots 10 and the vertically-ranging slots 11, which merge with said other slots. The screws 7 pass through these slots and serve to adjustably retain the keeper upon the seat 5. The keeper 8 being shiftable longitudinally and laterally is of great value in mounting and securing glass street-signs, which are usually of ring form applied in four sections.

It will be obvious to those skilled in the art to which the invention appertains that modifications may be made in details without departing from the spirit and scope of the same. Hence we do not limit ourselves to the precise construction and arrangement of parts hereinabove described, and illustrated in the accompanying drawings; but,

Having thus described our invention, what we claim as new, and desire to secure by Letters Patent, is—

1. A sign-holder comprising a support having a longitudinally-ranging rib or seat and a bottom flange, and an adjustable keeper coöperating with said support, substantially as described.

2. A sign-holder comprising a support having a longitudinally-ranging rib or seat centrally thereof, and a bottom flange, and a keeper adapted for endwise and lateral movement on said rib and having its base normally resting on said flange, substantially as described.

3. A sign-holder comprising a support having top and bottom flanges, and an adjustable keeper coöperating with said support and having its base normally resting on said bottom flange, substantially as described.

4. A sign-holder comprising a support having top and bottom flanges, said top flange being provided with an open slot, and an adjustable keeper coöperating with said support and having its base normally resting on said bottom flange, substantially as described.

5. A sign-holder comprising a support having top and bottom flanges, said top flange being directed inward and provided with an open slot, and an adjustable keeper coöperating with said support and having its base

normally resting on said bottom flange, substantially as described.

6. A sign-holder comprising a support having top and bottom flanges, said top flange being provided with an open slot, and said support having a longitudinally-ranging rib or seat, and a keeper adapted and arranged for endwise and lateral movement on said rib or seat and having its base provided with trans-

verse extensions or arms, which normally rest

on said bottom flange, substantially as described.

In testimony whereof we have hereunto signed our names in the presence of two subscribing witnesses.

ARTHUR E. SHAW.

EDWARD S. SANDERSON.
